UNITED STATES PATENT OFFICE.

CHARLES HAMMER, OF BROOKLYN, NEW YORK.

CLOSURE FOR BOTTLES OR JARS.

1,160,597.

Specification of Letters Patent. Patented Nov. 16, 1915.

Application filed August 8, 1912. Serial No. 714,144.

To all whom it may concern:

Be it known that I, CHARLES HAMMER, a citizen of the United States, residing at Brooklyn, in the county of Kings and State 5 of New York, have invented a new and useful Improvement in Closures for Bottles or Jars, of which the following is a specification.

This invention relates to closures for bottles or jars.

The principal object of the invention is to provide a flat metal cap which can be screwed or locked on a bottle or jar formed with a single continuous screw thread.

15 With the foregoing and other objects in view which will appear as the description proceeds, the invention resides in the combination and arrangement of parts and in the details of construction hereinafter described 20 and claimed, it being understood that changes in the precise embodiment of invention herein disclosed can be made within the scope of what is claimed without departing from the spirit of the invention.

25 In the accompanying drawing forming part of this specification,—Figure 1 is a side elevation of a jar provided with a cap or closure constructed in accordance with the present invention. Fig. 2 is a bottom 30 plan view without the cover plate; Fig. 3 is a vertical section through the upper end of the jar shown in Fig. 1; Fig. 4 is a plan view of the upper end of the jar showing the single continuous screw thread; Fig. 5 is an 35 enlarged vertical sectional view.

Like reference numerals indicate corresponding parts in the different figures of the drawing.

The numeral 1 indicates the upper end of 40 the jar or bottle which preferably is formed or molded with an annular rib 2 from which extends upward the usual single continuous spiral thread 3.

Heretofore, so far as I am aware, it has 45 been customary to employ what is known as a "screw cap" for closing a bottle or jar having a single continuous spiral thread, the thread or screw of the cap being of complementary form to the thread of the 50 jar or bottle. The present invention aims to dispense with the expense of rolling or forming a continuous thread in the metal cap and yet adapt the cap to be employed on a bottle having a single continuous 55 thread. To this end, the cap 4, as shown

in Fig. 5, is formed with a depending annular flange 5, and the flange 5 is pressed or punched inwardly at two opposite points, as indicated at 6—6 to provide short ribs which are intended to engage the thread of 60 the jar or bottle. Each of the ribs 6, as shown best in Fig. 1, is formed at such an incline that it will parallel the pitch of the thread of the jar or bottle.

In forming the ribs or projections 6—6 65 it is necessary to dispose them in different horizontal planes, that is to say, the different ribs are placed at different distances between the upper and lower portions of the flange 5. The reason for this arrangement of the ribs is that the portions of the screw thread to be engaged by one rib are located in a different horizontal plane from the portions of the thread to be engaged by the opposite rib. While the cap has been 70 described as having two ribs, it will be understood that any other desired number of such separated ribs may be employed, but in all cases it is necessary, where the ribs are arranged around the flange, to have them 75 disposed in different horizontal planes.

As will appear from the Figs. 1 and 2, the projections 6 are preferably somewhat elongated and provided with abrupt ends. This construction makes the projections sufficiently long to provide a good engagement 85 between the projections and the threaded mouth of the bottle or other storage vessel to which the cap or closure is applied.

I have found that two ribs or projections 90 6 gives the best results because this number enables me to locate one rib near the usual roughened portion provided at the top of the flange to give a good grip to the hand of the user; and the other near the edge of the 95 flange; which is strengthened, as by turning or curling over this edge. The roughened portion is preferably made by corrugating the flange near the top; and these corrugations not only roughen the flange, but of course strengthen it as well. The slope of the ribs or projections is made to correspond with the pitch of the thread 3; but the vessel and the cap are so designed that the slope of the projections is so slight that the upper 100 part of the upper rib and the lower part of the lower rib will be in close proximity to the corrugations and the turned over edge respectively over substantially their whole 105 lengths. By thus locating each rib closely 110

adjacent to a portion of the flange which is strengthened, the cap can be screwed on the vessel very tightly without any risk of deformation. For example, any downward pressure on the upper rib will be taken care of by the corrugations, and similar pressure on the lower will be counteracted by the curled edge. Moreover, by restricting the degree of inclination as stated, and thus 10 keeping the ribs near to the corrugations and the curled edge over their whole lengths, the stresses due to the pressure of the thread 3 on the ribs are prevented from concentrating, but are distributed uniformly over a 15 material extent of the corrugated portion and the curled edge; and the reinforcing effect of these parts of the flange is thereby rendered a maximum.

The bottle cap may be formed with either 20 a closed or open top. In the form of invention illustrated, an open-top cap is used. The opening in the top of the cap is indicated by the reference numeral 7 and the flange of the cap 4, surrounding the opening 7 is preferably ribbed or rolled upwardly, as indicated at 8. The opening 7 in the top of the cap preferably is closed by a plate 9 which is dished or bulged downwardly at its center, as indicated at 10 and is provided 30 with an outward extending flange 11 which rests upon the upper edge of the bottle neck 1, and is held securely thereon by the cap 4.

The flange of the cap may be stiffened by strengthening the lower edge of the same, 35 for example by providing a bead shown clearly in the drawings and extending entirely around the lower edge of the flange.

In using the closure of the present invention, the plate 9 is first placed upon the bottle neck and the cap 4 is then screwed into 40 closed position, in the same manner in which a screw cap is closed.

What is claimed is:

1. A closure for a storage vessel comprising a top and a flange, the flange being provided with a plurality of projections on its inner surface, each of said projections being inclined with respect to the top and elongated a material distance circumferentially 45 of the flange, and being united to the flange at all points, said projections further being located in close proximity to a strengthened

portion of the flange over nearly their whole lengths.

2. A closure for a storage vessel comprising a top and a flange, the flange having a strengthened portion near the top and another strengthened portion adjacent its edge, and having a pair of projections on its inner surface between said strengthened portions, 60 and located at different distances from the top, one of said projections being arranged in close proximity over substantially its whole length to the strengthened portion of the flange near the top, and the other in 65 close proximity over substantially its entire length to the other strengthened portion.

3. A closure for a storage vessel comprising a top and a flange, the flange having a strengthened portion near the top and another strengthened portion adjacent its edge, and having a pair of projections on its inner surface, each of which is elongated circumferentially of the flange and united 75 thereto at all points, one of said projections being located in close proximity to the strengthened portion near the top, over substantially its entire length, and the other projection being arranged in close proximity 80 over substantially its entire length to the other strengthened portion.

4. A closure for a storage vessel having a single continuous thread adjacent the mouth of the same, said closure comprising a flange 85 having a number of projections on its inner surface, said projections being elongated and having abrupt ends and being located at different distances from the edge of the flange, said top having an opening and being provided with a rib surrounding said opening, and a dished plate adapted to fit over the mouth of the vessel and having an outward extending rim to contact with the mouth of the vessel and to be engaged by 90 the rib portion of the top of the closure.

In testimony that I claim the foregoing as my own, I have hereto affixed my signature in the presence of two witnesses.

CHARLES HAMMER.
